ROGER FINNEGAN, OF NEW YORK, N. Y.

Letters Patent No. 69,978, dated October 22, 1867.

IMPROVEMENT IN HOISTING APPARATUS.

The Schedule referred to in these Letters Patent and making part of the same.

TO ALL WHOM IT MAY CONCERN:

Be it known that I, ROGER FINNEGAN, of the city, county, and State of New York, have invented a new and improved Hoisting Apparatus; and I do hereby declare that the following is a full, clear, and exact description thereof, which will enable others skilled in the art to make and use the same, reference being had to the accompanying drawings, forming a part of this specification, in which—

Figure 1 represents a front elevation, partly in section, of my improved hoisting apparatus.

Figure 2 is a vertical transverse section of the same, the plane of section being indicated by the line *xx*, fig. 1.

Figure 3 is a detail sectional view of the clamping device.

Similar letters of reference indicate corresponding parts.

This invention relates to a new manner of operating a hoisting apparatus, and consists in arranging a pair of oscillating clamps, which are fitted around the endless rope, by which the drum is revolved, and which can be set in motion by oscillating a horizontal axle. The axle is by means of ropes connected with the aforesaid clamps, and as it is oscillated it alternately throws one clamp into and the other out of gear with the endless rope. That clamp which is made to grasp the rope is at the same time drawn down, while the other free clamp is moved up, to grasp the rope at a higher point, and thus the endless rope is continually drawn over the drum, thereby revolving the same.

A represents the drum of a hoisting apparatus mounted in a suitable frame, B. C is the endless rope, passing around the drum. D D' are two levers, pivoted each with one end to the frame B, while its other end is provided with a tubular shank, *a a'*, through which the rope passes. The lever D is arranged above the lever D', and the rope passes through both tubes *a* and *a'*. From each tube project two (more or less) lugs *b b'*, towards that side which is opposite to the body of the lever D D'. To these lugs are pivoted levers E E', the lever E to D, and the lever E' to D', as shown. A curved cam, *e*, formed on the inner end of each lever E E', fits through a slot in each tube *a* into the interior of the same. The inner edge of this cam *e* is so arranged that the rope is clamped between the lower end of the cam and the opposite side of the tube, when the free end of the lever D or D' is turned up, and that of the lever E or E' forced down, as shown in figs. 1 and 3; while, when the free end of the lever D or D' is forced down, and that of the lever E or E' pulled up, the edge of the cam *e* will be parallel with the opposite side of the tube *a* or *a'*, and the rope C will therefore not be clamped by the lever E or E', as shown at *a'*, in figs. 1 and 3. The free ends of the levers E and E' are secured to a rope, F, which is with both ends secured to a disk, G, mounted on or to two cranks, projecting from a horizontal shaft, H, the rope passing around a friction-roller, I. The levers E and E' are secured to the two arms of the rope F, so that when the shaft H is oscillated, the end of one lever will be raised, and that of the other will be lowered; thereby one lever, E or E', will, during every other stroke of the shaft H, be brought with its free end up, so as to grasp the rope C, while the other lever E or E' is at the same time drawn down and releases the rope C. When, then, the shaft H is turned, the upward inclined lever will be drawn down, carrying with it the rope C, while the downward inclined lever will be drawn up, without grasping the rope C, so as to be brought into position to clamp it during the next stroke. When it is desired to release the rope C so as to unwind the hoisting-rope J from the drum A, it is only necessary to bring the two levers D E and D' E' into nearly level positions, and by then bearing upon the levers D D', near the tubes *a*, thereby the pivoted ends of the levers D D' and E E' are inclined downwards, and the rope C is relieved. This can be done by connecting the levers D and D' by means of a cord, K, as shown. The shaft H can be set in motion directly or by means of gear-wheel connections with another oscillating shaft, as may be desired. It will be seen that by this arrangement much power is gained, and that the rope C, when a weight is being elevated, is always clamped so that the use of a generally ineffective brake on the drum A is dispensed with. The tubes *a* are provided with set-screws *d d'*, which can be screwed against the cams *e* so as to throw the same against the rope, in case a thinner rope is employed, or draw it off where a thicker rope is used.

Having thus described my invention, what I claim as new, and desire to secure by Letters Patent, is—

1. The levers D and D', when provided with tubes *a* and *a'*, in combination with the levers E and E', having

cam-projections ϵ , all made and operating substantially as herein shown and described, so that each set of levers will clamp the endless rope C during every alternate stroke, as set forth.

2. The levers D and D' and E E', when arranged as described, in combination with the rope F and oscillating shaft H, all made and operating substantially as herein shown and described.

3. The arrangement of the cord K, levers D D' E E', and tubes α α' , as herein described for the purpose specified.

4. Providing the tubes α α' with set-screws d , substantially as and for the purpose herein shown and described.
